UNITED STATES PATENT OFFICE

ALEXIS V. LAPTEFF, OF DETROIT, MICHIGAN, ASSIGNOR TO HARRINGTON & KING PERFORATING COMPANY, OF CHICAGO, ILLINOIS, A CORPORATION OF ILLINOIS

DESIGN FOR A GRILLE PANEL

Application filed May 9, 1932. Serial No. 43,758. Term of patent 14 years.

To all whom it may concern:

Be it known that I, ALEXIS V. LAPTEFF, a citizen of Russia, residing at Detroit, in the county of Wayne and State of Michigan, have invented a new, original, and ornamental Design for a Grille Panel, of which the following is a specification, reference being had to the accompanying drawing, forming a part thereof.

In the drawing:

The figure is a face view of a grille panel embodying my new design, the panel being flat and of immaterial thickness.

I claim:

The ornamental design for a grille panel substantially as shown and described.

ALEXIS V. LAPTEFF.
